UNITED STATES PATENT OFFICE

170,784

ATTACHMENT FOR BICYCLES IN REPRESENTATION OF A PONY

Brennan B. West, Jr., Cleveland Heights, Ohio

Application November 28, 1952, Serial No. 22,468

Term of patent 14 years

(Cl. D34—15)

To all whom it may concern:

Be it known that I, Brennan B. West, Jr., a citizen of the United States, residing at Cleveland Heights, county of Cuyahoga, and State of Ohio, have invented a new, original, and ornamental Design for an Attachment for Bicycles in Representation of a Pony, of which the following is a specification, reference being had to the accompanying drawing, forming part hereof.

Fig. 1 is a side elevational view of an attachment for bicycles in representation of a pony, showing my new design;

Fig. 2 is a plan view of the same, and

Fig. 3 is a fragmentary cross-sectional view thereof, taken on line 3—3 in Fig. 1; and

Fig. 4 is a fragmentary cross-sectional view thereof, taken on line 4—4 in Fig. 1.

I claim:

The ornamental design for an attachment for bicycles in representation of a pony, substantially as shown.

BRENNAN B. WEST, JR.
